UNITED STATES PATENT OFFICE.

JAMES W. RUMSEY, OF WEST BERKELEY, CALIFORNIA, ASSIGNOR OF ONE-HALF TO
FRANK T. HAYS, OF CHICAGO, ILLINOIS.

CAR-DOOR.

1,215,714.

Specification of Letters Patent. Patented Feb. 13, 1917.

Application filed July 14, 1915. Serial No. 39,828.

To all whom it may concern:

Be it known that I, JAMES W. RUMSEY, a citizen of the United States of America, and a resident of West Berkeley, county of 5 Alameda, State of California, have invented certain new and useful Improvements in Car-Doors, of which the following is a full and clear specification, reference being had to the accompanying drawings, in which is 10 represented a horizontal sectional view of a sufficient portion of a doorway to illustrate my invention.

This invention has relation to railway cars in which the door slides horizontally back and forth across the door opening, and when closed is clamped or crowded into close contact with the door frame structure for the purpose of preventing admission of moisture, etc., into the car; the present improvements are intended to provide simple means for effectively sealing the rear end of the door against the admission of moisture, air, dust, etc., as more fully hereinafter set forth, the invention being especially, though not 25 exclusively, applicable to refrigerator cars.

In the drawing, only the right hand portion of the door structure is illustrated, the door being designated by *a*, the side of the car by *b*, and the metal door post by *c*, 30 this post being provided along its outer vertical edge with a flange or plate-like extension *d* whose front face lies parallel with the side face of the car. Between this plate *d* and the adjacent face of the car wall is 35 clamped, by means of a bolt or bolts *e* or otherwise, a fibrous packing strip *f* which consists preferably of a body of felt inclosed in canvas. The outer edge of this packing strip projects beyond a shoulder *g* formed 40 in the inner face of the plate *d*, so that between the reduced edge of the plate *d* and the outer edge of packing *f* is formed a longitudinal pocket.

45 Affixed to the inner face of the door is a metal strip *h* having a flange *i* extending along the vertical rear edge of the door, suitable bolts or rivets *j* being employed for affixing this angular metal member to the rear edge of the door. Clamped between 50 the strip *h* and the inner face of the door is

packing strip *k* preferably consisting of a body of felt covered with canvas and terminating short of the forward edge of plate *h* and the rear face of the door.

With a structure such as described, when 55 the door is slid into closed position, the forward edge of the plate *h* will enter the socket or pocket formed by the projecting edge of packing strip *h* and abut against shoulder *g*, while the reduced edge *d'* of plate *d* will 60 enter the pocket formed under the free edge of plate *h* and abut against the packing strip *k*, thereby forming a thoroughly compact joint throughout the length of the rear edge of the door. With this joint, it will be seen 65 that for moisture, etc., to pass the same it will have to take a very circuitous passage in which there are practically three sealing points, namely, where member *d'* abuts against packing *h*, where the front edge of 70 the plate *h* abuts against shoulder *g*, and where the packing *f* bears against the inner face of plate *h*. With a joint of this character, it would be practically impossible for moisture to enter the car, even should the 75 space between member *h* and the car wall be flooded by heavy rains and wind pressure. This joint will also, when used in refrigerator cars, afford a practical seal against admission of warm air, dust, etc.

Having thus described my invention, what I claim is:

1. In combination with a car wall and a door post structure embodying an abutment plate supported at a distance from the outer 85 face of the car wall, said abutment plate being provided with a longitudinal shoulder along its inner face, a packing strip clamped between said abutment plate and the adjacent face of the car wall, a slidable car door 90 having fastened to its inner face a metal strip adapted to overlap upon the reduced edge of the abutment plate to contact with the shoulder thereon and the packing held thereby, and another packing strip clamped 95 between said metal strip and the inner face of the door, for the purpose set forth.

2. In combination, a car wall and a door post structure having an abutment plate supported at a distance from the outer face 100

of the car wall, a packing strip being clamped against the face of the car wall by said abutment plate, a car door having clamped on its inner face a metal strip adapted to overlap the abutment plate and engage the packing strip therebehind, and a packing strip clamped against the door by said metal strip and adapted to contact with

the edge of the abutment plate, for the purpose set forth.

In testimony whereof I hereunto affix my signature in the presence of two witnesses.

JAMES W. RUMSEY.
